UNITED STATES PATENT OFFICE.

LIONEL A. CARTER, OF ST. LOUIS, MISSOURI, ASSIGNOR OF ONE-HALF TO WALTER F. KOKEN, OF ST. LOUIS, MISSOURI.

INTERNAL-COMBUSTION ENGINE.

1,202,802.

Specification of Letters Patent. Patented Oct. 31, 1916.

Application filed July 6, 1914. Serial No. 849,255.

To all whom it may concern:

Be it known that I, LIONEL A. CARTER, a British subject, residing at St. Louis, Missouri, have invented a certain new and useful Improvement in Internal-Combustion Engines, of which the following is a full, clear, and exact description, such as will enable others skilled in the art to which it appertains to make and use the same.

10 This invention relates to internal combustion engines of the type in which a relatively small charge of combustible gas is compressed to the point of ignition so as to produce a flame which ignites the mixture in 15 the main cylinder of the engine that has been compressed on the compression stroke of the piston.

One object of my invention is to provide an internal combustion engine of the general type referred to or an ignition device 20 for such engines which is so designed that the pressure created in the cylinder on the compression stroke of the piston is utilized to actuate a part or member which causes a 25 comparatively small charge of gas in a firing chamber or auxiliary cylinder to be compressed to the ignition point, thereby producing an efficient and more reliable ignition device than those that have heretofore been 30 designed, which comprised springs, levers, or other moving parts for actuating the member that compressed the firing charge to the ignition point.

Another object is to provide an internal 35 combustion engine of the type mentioned in which the member that compresses the firing charge to the ignition point has no connection with the piston in the main cylinder of the engine and is so arranged that there 40 is no danger of the firing charge being exploded before the mixture in the main cylinder has been compressed to the proper degree. And still another object is to provide a practicable engine of the type referred to 45 which is of simple construction and is so designed that the explosions in the main cylinder can be timed and regulated as accurately as in an engine provided with an electrical ignition device.

50 Other objects and desirable features of my invention will be hereinafter pointed out.

Figure 1 of the drawings is a vertical sectional view of an internal combustion engine constructed in accordance with my invention. Fig. 2 is a similar view showing the

parts in a different position. Fig. 3 is a detail top plan view of the means for varying the time that the explosions occur. Fig. 4 is a detail sectional view illustrating a slight modification of my invention which differs from the form shown in Fig. 1 in that no check valve is provided for the port that establishes communication between the main cylinder and the firing chamber. Fig. 5 is a vertical sectional view illustrating an internal combustion engine constructed in accordance with my invention, in which the firing chamber is at one side of the main cylinder of the engine. Fig. 6 is a similar view showing the parts in a different position. Fig. 7 is a horizontal sectional view taken on the line 7—7 of Fig. 5; and Fig. 8 is a horizontal sectional view taken on the line 8—8 of Fig. 5.

Referring to Figs. 1 to 3 of the drawings which illustrate the preferred form of my invention, A designates one of the main cylinders of an internal combustion engine, and B designates the piston that operates in said cylinder. A firing chamber or auxiliary cylinder C of relatively small area is provided for receiving a charge of combustible gas that is compressed to the point of ignition by a member which is actuated by the pressure created in the main cylinder A on the compression stroke of the piston B, the flame that is produced in said firing chamber passing into the main cylinder A and igniting the compressed charge in said cylinder.

In the form of my invention shown in Fig. 1 the firing chamber C is formed in a movable member 1, and a stationary member 2 projects into said chamber so as to act as a piston that compresses the gas in said chamber to the point of ignition when the member 1 is actuated in one direction by the pressure in the main cylinder A of the engine. The member 1 is reciprocatingly mounted in a sleeve 3 that is arranged in the head of the cylinder A in such a manner that the pressure in said cylinder will be exerted upwardly on the lower end of the member 1, said sleeve either being formed integral with the cylinder or provided with an externally 100 screw-threaded portion 3^a that can be screwed into the usual spark plug opening in the head of the cylinder. The stationary member 2 that constitutes the piston of the firing chamber C is carried by a cap 110

piece 4 that closes the upper end of the sleeve 3, and which is secured thereto by a cross pin 5, or in any other suitable manner, as shown in Figs. 1 and 2. Communication 5 between the main cylinder A and the firing chamber C is established by one or more ports, so as to permit a charge of gas to enter the chamber C on the compression stroke of the piston B in the main cylinder, 10 and also to permit the flame produced in the chamber C by the explosion of the charge therein to pass into the main cylinder A and ignite the compressed charge in said cylinder. In the form shown in Fig. 1 a 15 port 6 in the lower end of the member 1 permits a charge of gas to enter the firing chamber C when the piston B in the main cylinder is moved upwardly on its compression stroke, and a check valve 7 that is provided for said port traps the charge that 20 enters the firing chamber and prevents it from escaping therefrom when the member 1 starts to move upwardly to compress said charge, the flame that is produced in the 25 chamber C when the charge therein is exploded escaping into the main cylinder A through a port 8 in the check valve 7, as shown in Fig. 2. While I prefer to provide the device with a relatively large port 30 for admitting the charge to the firing chamber and use a check valve for trapping the charge in the firing chamber, I do not wish it to be understood that it is absolutely necessary to use a check valve, for, if desired, a 35 comparatively small port 6^a could be formed in the member 1, as shown in Fig. 4, so as to permit the charge to enter the firing chamber C and also permit the flame to pass through said port into the main cylinder A. 40 Means are provided for holding the member 1 at rest during the compression stroke of the piston B until the mixture in the cylinder A has been compressed to the proper degree, said means being so designed 45 that the member 1 will be released during the compression stroke of the main piston B and at such a period that the charge in the main cylinder A will be ignited at the proper time in the cycle of operations of the engine. 50 When the main piston B starts to move upwardly on its compression stroke the member 1 is securely locked so that it cannot move, consequently, a charge of gas flows from the main cylinder A through 55 the port 6 into the firing chamber C. As the main piston B approaches the end of its compression stroke the member 1 is released and the pressure that has been created in the cylinder A causes said member 1 to move 60 upwardly, and thus compress the explosive charge in the chamber C to the ignition point, the flame that is produced by the explosion of the charge in the chamber C passing into the main cylinder A through the 65 port 8 in the check valve 7, and thus igni-

niting the compressed gas in the cylinder A.

Various means may be used for locking the member 1 and releasing it at the proper period in the cycle of operations of the engine, the means herein shown for this purpose consisting of a locking device 9 in one side of the sleeve 3 that enters a groove 10 in the upper end portion of the member 1, said locking device being controlled by a lever 11 that is moved in one direction by means of a spring 12 and which is moved in the opposite direction by means of a timing cam 13 on a constantly rotating shaft 14. The cam 13 is splined to the shaft 14 and a 70 controlling mechanism, consisting of a yoke lever 15 and a rod 16, are provided for shifting the cam 13 longitudinally of the shaft 14, as shown in Figs. 1 and 3 so as to vary the time that the cam 13 actuates the lever 75 11. The spring 12 normally holds the lever 11 in such a position that the device 9 will either be in engagement with the member 1 or in position to engage the groove 10 in said member. When the high point on the 80 cam 13 engages the roll 11^a on the lower end of the lever 11 the locking device 9 will be disengaged from the member 1, and thus permit the member 1 to move upwardly through the influence of the pressure in the cylinder 85 A. The explosion produced in the firing chamber C tends to move the member 1 downwardly back to normal position, and the suction produced in the main cylinder A on the power stroke of the piston also tends to move the member 1 downwardly. If desired, however, a spring 17 can be arranged 90 between the upper end of the member 1 and the cap member 4 in the sleeve 3, so as to insure the member 1 moving downwardly 95 back to normal position. A stop 3^b at the lower end of the sleeve 3 limits the downward movement of the member 1 and prevents said member from projecting into the cylinder A. By changing the position of the timing cam 13, or, in other words, shifting said cam longitudinally of its shaft 14, the timing of the explosions in the cylinder 100 A can be controlled as accurately as in an engine equipped with an electrical ignition 105 device.

Various means may be employed for lubricating the movable member 1 and the stationary piston 2 with which it cooperates, and in Fig. 1 I have shown one means that may be used for this purpose, consisting of an oil pipe 18 for admitting oil to the sleeve 3 at such a point that oil can flow downwardly over the side walls of said sleeve and over the exterior of the stationary piston 2, which is provided at its lower end with oil 110 grooves 19.

In the form of my invention shown in Figs. 5 to 8, inclusive, the firing chamber C' is arranged at one side of the main cylinder 115 130

A' adjacent the upper end of same, and the movable member 1^a which compresses the charge in the chamber C' to the point of ignition is so arranged that the pressure in the cylinder A' will force it downwardly into the chamber C'. A port 6^b in the side walls of the cylinder A' establishes communication between the firing chamber C' and the main cylinder A', and means are provided for holding the member 1^a in an elevated position, as shown in Fig. 5, during the compression stroke of the piston B' in the main cylinder so that a charge of gas can enter the firing chamber at the proper period in the cycle of operations of the engine and the member 1^a released so that the pressure in the cylinder A' will be exerted downwardly on the upper end of the member 1^a, and thus cause the firing charge in the chamber C' to be exploded, the flame that results from said explosion passing through a port 8^a preferably formed in the member 1^a and igniting the compressed gas in the main cylinder A'. The member 1^a is carried by a reciprocating part or slide 20 that moves vertically in a stationary guide-way 21, said slide being provided with an extension 22 that coöperates with a constantly rotating cam 23 which causes the slide 20 and the member 1^a thereon to move upwardly and remain at rest while the mixture in the main cylinder A' is being compressed on the compression stroke of the main piston B'. The cam 23 is so designed that it will pass out of engagement with the block 22^a on the lower end of the guide 22 while the main piston B' is moving upwardly on its compression stroke, and means are provided for shifting said cam 23 longitudinally of the shaft 24 which carries same so as to vary the period in the cycle of operations of the engine that the cam 23 releases the slide 20, and thus enables the timing of the explosions to be controlled accurately, the means herein shown for changing the position of the cam consisting of a shiftable lever 15 and a link 16 of similar construction to the means used for this purpose in the form of my invention illustrated in Figs. 1 to 3. While I prefer to arrange the firing chamber C' vertically and at one side of the main cylinder A', I wish it to be understood that my invention is not limited to such a construction, for the firing chamber C' and the movable member 1^a inside of same could be arranged in various other positions without departing from the spirit of my invention. Furthermore, while I prefer to form the flame port 8^a in the member 1^a, this is not essential, so long as said flame port is located in such a position that the flame can pass from the firing chamber into the main cylinder. The firing chamber C' is substantially V-shaped in cross section, and the guide 21 in which the member 20 slides, is

provided with inclined side walls that are disposed at the same angle as the side walls of the firing chamber C'. The member 1^a is substantially V-shaped in cross section and the slide 20 which carries said member is substantially wedge-shaped in cross section. The rear wall 25 of the guide 21 can be adjusted laterally toward the cylinder A' so as to compensate for wear on the slide 20, and thus insure a practically gas-tight joint between the slide 20 and the guide between which it moves. As shown in Fig. 5 the inner face of the adjustable wall 25, against which the rear face of the slide bears, is straight and parallel to the path of movement of the piston B', but the rear face of said wall 25 and the coöperating faces on the guide 21, against which it bears, are inclined so that when said wall 25 is moved downwardly the front face of same will be brought closer to the wall 26 of the guide, against which the front side of the slide 20 bears. The means herein shown for securing the adjustable wall 25 of the guide 21 in adjusted position consists of bolts 27 that pass through a vertically disposed elongated slot 28 of the guide and is shown clearly in Figs. 5 and 7.

In both forms of my invention a small charge of combustible gas is forced into the firing chamber during the compression stroke of the piston in the main cylinder and at the proper period in the cycle of operations of the engine the movable part which compresses the charge in the firing chamber is released so that the pressure in the main cylinder will actuate it and cause it to compress the firing charge to the point of ignition, the flame that results from the explosion in the firing chamber passing into the main cylinder and igniting the compressed gas therein. No springs, levers or other mechanically operated parts are depended upon to actuate the member which compresses the firing charge to the point of ignition, but, on the contrary, the pressure in the main cylinder of the engine is utilized to actuate said member, and consequently, the engine is more efficient than the engines of this type which have heretofore been designed. The movable member that causes the explosion in the firing chamber to occur is held securely locked until the mixture in the main cylinder has been compressed to the proper degree, and as the period in the cycle of operations at which said member is released can be varied by simply changing the position of the cam 13 in the form shown in Fig. 1, or the cam 23 in the form shown in Fig. 5, the timing of the explosions can be controlled as accurately as in an engine provided with an electrical ignition apparatus.

My improved ignition device comprises few parts, and, as shown in Fig. 1, it can be

5 applied easily to an engine equipped with an electrical ignition apparatus, owing to the fact that the guide 3 which carries the movable member 1 and also the stationary piston, that forms one of the end walls of the firing chamber is so designed that it can be screwed into the usual spark plug opening in the head of the cylinder of the engine.

10 Having thus described my invention, what I claim is:

15 1. In an internal combustion engine, a cylinder, and relatively movable members forming a separate firing chamber that is adapted to receive a firing charge, one of 20 said members being interposed between the firing charge in said chamber and the gases in the cylinder and adapted to be moved in a direction to compress the firing charge in said chamber to the point of ignition, by the 25 direct pressure which the gases in the cylinder exert on said member during the compression stroke of the piston.

30 2. In an internal combustion engine, a cylinder, a separate firing chamber that is adapted to receive a firing charge, said chamber being formed by relatively movable members, one of which is interposed between the firing charge in said chamber and the gases in the cylinder and adapted to be 35 moved in a direction to compress the firing charge in said chamber to the point of ignition, by the pressure which the gases in the cylinder exert on said member during the compression stroke of the piston, and means 40 for enabling the period at which said firing charge is ignited to be varied so as to control the timing of the explosions in the cylinder of the engine.

45 3. In an internal combustion engine, a cylinder, a piston in said cylinder, an ignition device comprising a firing chamber, means for permitting a relatively small charge of combustible gases to enter said firing chamber on the compression stroke of 50 the piston in the cylinder of the engine, and a movable member forming part of said chamber and interposed between the gases in the cylinder and in said firing chamber, said member being moved in a direction to compress 55 the charge in said firing chamber to the point of ignition, by the pressure which the gases in the cylinder exert on said member during the compression stroke of the piston.

60 4. In an internal combustion engine, a cylinder, a piston in said cylinder, an ignition device comprising a firing chamber that communicates with the main cylinder of the engine, and which is adapted to receive a 65 relatively small charge of gas from the cylinder during the compression stroke of the piston in the cylinder, said chamber being formed by relatively movable members, one of which is interposed between the gases in 70 the firing chamber and in the cylinder and

75 adapted to be moved in a direction to compress the firing charge to the point of ignition, by the pressure which the gases in the cylinder exert on said member during the compression stroke of the piston, and means 80 for holding said movable member at rest while the charge in the main cylinder is being partly compressed.

85 5. In an internal combustion engine, a cylinder, a piston in said cylinder, an ignition device comprising a firing chamber that communicates with the cylinder of the engine and which is adapted to receive a relatively small charge of combustible gas during the compression stroke of the piston in 90 the cylinder, said chamber being formed by relatively movable members, one of which is moved directly by the pressure created in the cylinder on the compression stroke of the piston to compress the charge of combustible 95 gas in the firing chamber to the point of ignition so as to produce an explosion which fires the compressed gas in the cylinder, and means for holding said member at rest while the mixture in the cylinder is being compressed, said means being so designed that said movable member is released after the mixture in the cylinder has been compressed and when the piston is near the upper end of its stroke.

100 6. In an internal combustion engine, a cylinder, a piston in said cylinder, a firing chamber that is adapted to hold a relatively small charge of combustible gas, and a port that establishes communication between said 105 firing chamber and the cylinder of the engine, said chamber being formed by relatively movable members, one of which is interposed between the gases in the cylinder and in said firing chamber and adapted to 110 be moved in a direction to compress the charge in said firing chamber to the point of ignition and thus produce an explosion which fires the compressed gases in the cylinder of the engine, by the pressure which 115 the gases in the cylinder exert directly on said member during the compression stroke of the piston.

120 7. In an internal combustion engine, a cylinder, a piston in said cylinder, a firing chamber that is adapted to hold a relatively small quantity of combustible gas, a port that establishes communication between said 125 firing chamber and the cylinder of the engine, said chamber being formed by relatively movable members, one of which is actuated directly by the pressure created in the cylinder on the compression stroke of the piston for compressing the charge of combustible gas in said firing chamber to 130 the point of ignition so as to produce an explosion which fires the compressed gas in the cylinder of the engine, and an automatically-operating mechanism that holds said member at rest during the compression 135

stroke of the piston and releases it at such a time that the mixture in the cylinder will be ignited at the proper period in the cycle of operations of the engine.

- 5 8. In an internal combustion engine, a cylinder provided with a piston, a firing chamber of relatively small area formed by relatively movable members, a port for permitting gas to flow from the cylinder of the 10 engine into said firing chamber on the compression stroke of the piston in the cylinder, one of said movable members being interposed between the gases in the cylinder and in said firing chamber and adapted to be 15 moved in a direction to compress the charge in said firing chamber to the point of ignition, by the pressure which the gases in the cylinder exert on said member during the compression stroke of the piston, and a port 20 of relatively small cross-sectional area through which the flame passes from the firing chamber so as to ignite the compressed mixture in the cylinder.
9. In an internal combustion engine, a 25 cylinder provided with a piston, a firing chamber of relatively small cross-sectional area that communicates with the cylinder of the engine and which is adapted to receive a charge of gas from the cylinder, said 30 chamber being formed by relatively movable members, one of which is interposed between the gases in said firing chamber and in the cylinder and adapted to be moved in a direction to compress the charge in the 35 firing chamber to the point of ignition, by the pressure the gases in the cylinder exert on said member during the compression stroke of the piston, and an independent means for actuating said movable member 40 after the charge in the cylinder has been fired.
10. In an internal combustion engine, a cylinder, a piston in said cylinder, a firing chamber that communicates with a port 45 formed in the side wall of said cylinder adjacent the upper end of same and which is adapted to receive a firing charge, a movable member interposed between the firing charge in said chamber and the gases in the 50 cylinder and adapted to be actuated by the pressure in the cylinder on the compression stroke of the piston for compressing the charge in the firing chamber to the point of
- ignition, and means that moves said movable member in the opposite direction and holds it in such a position that a charge of gas can flow from the cylinder into the firing chamber on the compression stroke of the piston prior to the time said member starts to move to compress the charge in the firing chamber. 55
11. In an internal combustion engine, a cylinder, a firing chamber having a port through which a charge of combustible gas can pass from the main cylinder into said 60 firing chamber, a movable member arranged in such a manner that the pressure in the main cylinder will cause it to compress the charge of gas in said firing chamber to the point of ignition, a slide that carries said movable member, and an adjustable guide-way in which said slide travels. 65
12. In an internal combustion engine, a cylinder, a firing chamber, means for permitting a charge of combustible gas to pass 70 from the cylinder into said firing chamber, a movable member operated by the pressure created in said cylinder on the compression stroke of the piston for compressing the charge of gas in the firing chamber to the point of ignition, a slide of approximately wedge-shape in cross section that carries said movable member, and means for compensating for wear on said slide. 75
13. In an internal combustion engine, a cylinder, a firing chamber, means for permitting a charge of combustible gas to pass from the cylinder into said firing chamber, a movable member operated solely by the pressure of the gas compressed in the main 90 cylinder on the compression stroke of the piston for compressing the charge of gas in the firing chamber to the point of ignition, a reciprocating part to which said member is connected, and a cam coöoperating with 95 said part to restore said member after the charge in the firing chamber has been ignited.

In testimony whereof I hereunto affix my signature in the presence of two witnesses, 100 this twenty-seventh day of June 1914.

LIONEL A. CARTER.
